(57) **CLAIM**

The ornamental design for indoor thermometer, as shown and described.

DESCRIPTION

FIG. 1 is a first perspective view of an indoor thermometer showing my design;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the indoor thermometer showing a status when the indoor thermometer is being used. The broken lines are for environmental structures or boundaries and form no part of the claimed designs to be patented.
